UNITED STATES PATENT OFFICE.

OCTAVIUS R. WEBSTER, OF BELFAST, MAINE.

CAN-OPENER.

SPECIFICATION forming part of Letters Patent No. 278,379, dated May 29, 1883.

Application filed March 26, 1883. (No model.)

To all whom it may concern:

Be it known that I, OCTAVIUS RANDOLPH WEBSTER, of Belfast, in the county of Waldo, of the State of Maine, have invented a new and useful Improvement in Can-Openers; and I do hereby declare the same to be described in the following specification and represented in the accompanying drawings, of which—

Figure 1 is a top view, Fig. 2 a side elevation, and Fig. 3 a longitudinal section, of a can-opener containing my invention, the nature of such invention being defined in the claim hereinafter presented. Fig. 4 is a transverse section taken through the cutting-arms of the two levers. Fig. 5 is a bottom or under side view of the lever A, and Fig. 6 is a top view of the lever B.

In said drawings, A represents a lever slotted lengthwise in its shorter arm, as shown at a, and curved, and having in its longer arm, near its end, an eye or opening, b, for reception of the third finger of the right hand of a person. The shorter arm of the said lever I usually make straight on its lower edge, as shown at c, and pointed at its end, as represented at d. Extending through the slot a is another or cutting lever, B, the two levers being pivoted together or having a common fulcrum, e. The shorter arm of the lever B has a width at top equal to or a trifle less than that of the slot a, and such arm at its end terminates in a sharp chisel cutting-edge, g. Affixed to the longer arm of the lever A and extending into the slot a and under and against the longer arm of the lever B is a spring, C, the purpose of which is to force asunder the two arms in order to open the cutting-jaws or shorter arms or move them apart. The slot a increases somewhat in width from its lower part upward, in order to readily discharge the strip formed by the jaws in cutting a can.

The instrument, when used to open a can, cuts a strip of metal therefrom, which passes upward through the slot a. The pointed or sharp end of the cutting blade or arm of the lever B is first to be thrust into the can-head; or the pointed end of the jaw or shorter arm of the lever A may first be forced into the can-head to form an orifice therein for reception of the end of the shorter arm of the lever B. The party or person using the article is to insert the third finger of his right hand in the

eye b, and at the same time grasp the two levers between his thumb and fore or second finger of such hand. Having thus hold of the can-opener, and having inserted the shorter arm of the lever B in the head of the can, he with his thumb is to move the said lever successively, and to intermittently force it forward in a manner to cause the jaws to cut a strip from and in or around the can-head as occasion may require.

In this can-opener the slot a of the lever A is closed at its outer end, the lever being pointed at d beyond the slot. By having the slot closed at its outer end, the parts on each side of such slot are kept from spreading so as to loosen the pivot e when the instrument may be in use. The spring C, by being fixed to the slotted lever A and extended into the slot of such lever and against the longer arm of the lever B, becomes so arranged as not to be liable in any way to catch and pinch, on the levers being pressed together, a person's hand between it and the lever to which it is affixed, as would be the case were the spring attached to either of the levers near its outer end and extended between them and against the other lever. By forming the lever B with a chisel-edge at its end, it, with the part extending beyond the outer end of the slot e, can be used to cut off transversely a strip at its junction with a can-head, which could not be done were the slot to be open at the end of the shorter arm of the lever, and the end of the shorter arm of the lever B were pointed instead of being chisel-edge shaped.

I do not herein claim a can-opener as represented in the United States Patent No. 191,416.

I claim—

The improved can-opener, substantially as described, consisting of the lever A, provided with the slot a, arranged therein and closed at its front end, as explained, and of the lever B, pivoted to the lever A and extended through the slot, and having its shorter arm adapted to cut at its end as well as at its sides with the slot a, all being essentially as set forth.

OCTAVIUS R. WEBSTER.
